METHOD AND APPARATUS FOR RAPIDLY DRYING CASEIN CURD AND LIKE SUBSTANCES

William B. Winter, Belmont, Mass., assignor to Atlantic Research Associates, Inc., Newtonville, Mass., a corporation of Delaware

Application April 8, 1941, Serial No. 387,453

15 Claims. (Cl. 34—10)

This invention relates to an improved method and apparatus for rapidly drying solid particles of moist substances suspended in a stream of heated air.

It has heretofore been proposed to dry moist materials such as casein and other substances by feeding the materials in a finely divided state for suspension in a stream of heated air. The equipment proposed included a large and costly layout of tubing of considerable length and size which required a large installation space. While this heretofore proposed method of drying has materially reduced the time required as compared with the "tray and tunnel" and "rotary" types of driers, it is nevertheless objectionable, for the capacity it provides, as constituting bulky and relatively costly apparatus.

One of the objects of the present invention, therefore, is to provide an improved method of and apparatus for rapidly drying in a stream of heated air moist particles of substances wherein the apparatus for a given capacity requires less installation space than drying apparatus of similar character heretofore proposed.

Another object of the invention is to provide an improved method of and apparatus for rapidly drying in a stream of heated air particles of moist substances at a power consumption for a given capacity considerably less than required by drying apparatus of similar character heretofore proposed.

Another object of the invention is to provide an improved method and apparatus for drying moist substances wherein a great versatility of control is provided.

A further object of the invention is to provide an improved method and apparatus for drying small particles of wet substances wherein the particles are given individual treatment in accordance to the amount of drying required.

A still further object of the invention is to provide an improved drying apparatus which is simple, sturdy, compact and relatively economical to build and operate.

Further objects and advantages of the invention will become apparent from the following description of the method as well as from a later detailed description of apparatus by which the method can be carried out.

In its broader aspects, my improved method for rapidly drying solid particles of moist substances comprises feeding small particles of the substance for suspension in a stream of air heated to a suitable temperature and causing the air and particles entrained therein to move through a

chamber in a double vortex movement, whereby the coarser moisture retaining particles after being initially heated are separated from the air in the initial or outer vortex movement. The 5 finer particles which are substantially dried in passing through the outer vortex are retained in suspension and carried in a reverse direction centrally of the outer vortex through an inner vortex movement and thereafter separated from the air. The coarser moisture retaining particles which are separated from the drying air by the action of gravity and centrifugal force in the outer vortex are intercepted either by an inwardly deflecting surface or by additional drying air to direct and re-entrain the particles for movement in the inner vortex where they can also be carried off in a substantially dried condition for final separation from the air.

The temperature of the heated air initially contacted by the moist particles may be selected from a wide range depending, of course, upon the wetness of the particles to be dried and the effect which high temperatures have upon the quality of the material. For most moist materials a satisfactory temperature can be selected for use in my method above 200° F. and up to 20 as high as 350° F. The drying by my method is so rapid that the moisture absorbed by the heated air quickly reduces the initial temperature thereof so that when the particles have given up a large portion of their moisture, the 25 temperature of the surrounding air will have been correspondingly reduced so as not to be injurious to the dried or partially dried material.

30 For substances such as casein curd where the qualities thereof can easily be adversely affected by high temperatures and prolonged heating, temperatures as high as 320° F. have been used successfully in my method without adversely affecting the qualities of casein and without any substantial discoloration of the particles.

The additional air introduced into the flowing stream between the outer and inner vortices can 35 be of the same but is usually preferred to be lower than the initial temperature of the main stream of air. The temperature of the additional air, however, will depend upon the final degree of drying desired and the amount of drying accomplished by the main air stream.

Where substance of exceptionally high moisture content is to be dried two or more drying stages can be arranged, the exhaust from the second or third stage may be used in the first where this material is introduced, or the exhaust air from the first or second stage may be used in

the third; or the stages may be connected in any other arrangement depending upon the temperature and humidity of the air desired for the different stages. In a two-stage system, for example, particles of a substance such as casein having a moisture content of about 55 to 65% can be subjected by my method to air of a temperature of 320° F. in the first stage without adversely affecting the quality thereof. The casein discharged from the first stage would then have a temperature of about 100° F. and be about one-half dry, that is, reduced to a moisture content of about 30 to 35%. With this moisture content, the particles can be successfully subjected in the second stage to air temperatures also as high as 320° F. and should the moisture content of the particles be less than 30 to 35%, the heated air for the second stage can be tempered by admixing therewith exhaust air from the first stage.

Whether or not the same temperature is used for the air fed to each of a plurality of units, or whether or not more than one unit is used will depend upon the size of the particles, the moisture content thereof and the rate of diffusion of the moisture from the inside to the outside of the particles, and also on the load the drier can carry.

Briefly, a single unit of the apparatus comprises a cyclone chamber similar to that of a cyclone dust and air separator. The initial stream of air and the particles entrained therein flow in a large downward whirl or vortex into the chamber. In the lower portion of the chamber the downward direction of the air movement is reversed, the air and the fines suspended therein being caused to whirl upwardly as a small vortex within the larger vortex. The coarser moisture laden particles which are less easily dried are separated by centrifugal force from the air during movement through the outer vortex, the separated particles being further dried and reentrained in the flow by additional air introduced adjacent the bottom of the chamber.

The introduction of additional or secondary air to further dry and retrain the coarser moisture retaining particles for movement into the inner vortex may be brought about in any one of several ways. The additional air may be taken direct from the same source as the initial air or from the exhaust of the cyclone chamber itself, or from another drying unit and forced or drawn in tangentially at the bottom of the cyclone chamber. Where the additional air is forced into the chamber at the bottom thereof, a vertical or tangential inlet may be provided, or a small cyclone chamber arranged to exhaust directly into the lower end of the main cyclone chamber and thereby pick up the gravitating particles and carry them into the inner vortex. Then again, the additional air might be forced into the inner vortex by providing an axial flow fan or air current straightening vanes at the bottom of the cyclone chamber.

If suction is relied upon for introduction of the air streams, this may be carried out by providing a suitable fan at the exhaust duct, the introduction of the initial and additional air streams being controlled by suitably located dampers.

Under some conditions it is advantageous to place a conical deflector at the bottom of the chamber so as to deflect and guide upwardly toward the center of the drying chamber any

particles tending to separate from the air stream where the stream reverses its direction of flow.

In an additional embodiment of the invention, the moist particles are subjected to an initial drying step before they are introduced into the double vortex movement. The initial stream of air and entrained particles are first caused to whirl upwardly through a narrow space so that the coarser moisture laden particles, due to their tendency to gravitate downwardly counter to the upward flow of air are tumbled and re-entrained by the incoming heated air. After the stream of air has moved in an upward whirl for a determined distance, the air and entrained particles are caused to whirl through a double vortex movement in a cyclone chamber similarly as hereinbefore described.

In the above described method and its several modifications, the drying can be accomplished in a single stage because, although additional quantities of heated air can be introduced, the substance to be dried is not separated completely from the air with which it is initially contacted until the drying is substantially complete. With certain substances and degrees of wetness, two or more stages may be preferred as hereinbefore stated.

The drying with the double vortex movement for each stage of drying not only greatly reduces the size and number of chambers and therefore the installation space heretofore required for particle suspension driers, but a considerable saving in power consumption for a given capacity is also effected by my invention. This saving in power consumption is effected by utilizing the inner vortex of the cyclone chambers to prolong the contact relation between the heated air and the particles. The additional air introduced into the inner vortex serves to convey the substance to be dried into the inner vortex and can be used to add or lower the heat, and humidify or lower the humidity.

A better understanding of the method and of the forms of apparatus that can be used to carry out the method will become further apparent upon consideration of the following detailed description when taken in connection with the accompanying drawings, in which:

Figure 1 is a view in elevation partially in section, and showing the general arrangement of one of the embodiments of the apparatus for carrying out the method of my invention; Figure 2 is a plan view of the apparatus showing a separator construction;

Figure 3 is a fragmentary view in vertical section showing a modified form of the invention;

Figure 4 is a fragmentary view in elevation, partially in section, showing another embodiment of the apparatus; and

Figure 5 is a view in elevation, partially in section, and showing a further form of apparatus by which the method of my invention may be practiced.

Referring to Figures 1 and 2 of the drawings, a compact drier construction is shown comprising a casing 8 defining a conically shaped cyclone chamber 10 similar to a centrifugal dust and air separator. The chamber 10 has a tangential inlet 12 and a centrally disposed exhaust duct 14 extending through the upper portion thereof to a separator 30.

A stream of heated air is propelled by a power driven fan 16 from a heater 18 through a conduit 20 into which solid particles of wet substance of about 20 to 40 mesh are fed through a duct 22.

To facilitate the drying of the coarser particles, the substance may be rolled or otherwise shaped into flakes.

The finer of the particles are quickly dried by the heat of the drying air. The coarser particles which are not so quickly dried are separated therefrom after initial contact with the air by centrifugal force, provided, of course, that the coarser particles do not have a proportionately higher surface area than the finer particles. As the air whirls within the drying chamber, it moves downwardly in a large outer vortex 21, and then upwardly in a smaller vortex 23 centrally of the vortex 21. The upwardly whirling air together with the suspended particles are carried out of the drying chamber through the duct 14. The coarser moisture retaining particles which are separated from the air during the downward whirling movement gravitate adjacent the walls of the chamber toward the bottom thereof.

In order to obtain adequate drying of the coarser particles of substance quickly and before undesirable case hardening thereof is effected, the separated particles are intercepted by an additional stream of heated air introduced adjacent the bottom of the chamber. This can be accomplished in several ways. One way of accomplishing this, as shown in Fig. 1, includes a conduit 24 which is connected tangentially to the bottom 25 of the main cyclone casing. Heated air is fed by a fan 26 from the heater 18 through the conduit 24 tangentially into the bottom portion of the chamber 10. If desired, the air may be tempered by introduction of cool air at 27. The air thus introduced into the bottom of the chamber 10 is given a whirling movement adapted to pick up any particles gravitating to the bottom thereof and carry them in a whirling movement into the inner vortex.

Another method by which additional air can be advantageously introduced at the bottom of the chamber 10 is by connecting thereto a smaller cyclone chamber 28, as illustrated in Fig. 3. Additional air introduced tangentially into the chamber 28 whirls upwardly through the bottom 25 of the chamber 10 to pick up particles gravitating toward the bottom of the chamber 10. Should the chamber 10 become overloaded or receive a quantity of particles too heavy for the air stream to easily reentrain, the bottom cyclone 28 can then receive the overflow.

In order to insure that the additional air introduced by way of the chamber 28 does not exert too great a centrifugal force upon reentrained particles as the air passes into the chamber 10, the port 36 may be provided with a plurality of air current straightening vanes 38. These vanes translate part of the whirling action of the air into a vertical component which insures the conveyance of the reentrained particles well upwardly into the inner vortex 23.

The bottom of the chamber 28 is provided with a withdrawal duct 29 whereby foreign and overweight particles may be collected and withdrawn, or a part or all of the product may be collected at this point, and if desired subjected to a further drying stage.

The exhausting air and entrained particles are conveyed from the duct 14 through the separator 30 whereby the particles are separated from the air, the air being exhausted through the duct 32 and the particles through the duct 34. A damper 33 may be used to facilitate the separation.

In order to preserve heat, the casing and conduits of the system are covered by a suitable layer of insulation 56.

While the incoming air at 12 is introduced tangentially of the chamber to provide a whirling movement for the air and entrained particles, one or more vanes 60 may be provided to entrain the particles for a longer drying period.

From the foregoing it will be observed that the particles of substance fed through the duct 22 are rapidly subjected to a high temperature, whereupon a large percentage of the moisture contained in the material is quickly absorbed by the heated air, thereby materially lowering the temperature of the air and partially saturating the same. Since air when substantially saturated has little further rapid drying power, my method and apparatus provides for the separation from this initial air of at least those particles which still retain a substantial portion of moisture. The partially saturated air together with the finer particles which are more easily dried are permitted to pass out of the chamber 10 shortly after entrance thereto. The coarser moisture retaining particles which have been substantially raised in temperature by the initial drying treatment are intercepted and further treated by an additional stream of heated air of a dryness capable of quickly completing the drying thereof.

The drying of the particles, both fine and relatively coarse, is only a matter of seconds.

This rapidity of the drying operations, while highly efficient and capable of use in small sized installations, can be advantageously used in the drying of casein curd and similar wet substances. By drying the curd immediately after the washing and pressing operations the increase in acidity heretofore experienced in the drying of casein is substantially avoided. The heating period of the drying operation being extremely short, and since the dry product may be immediately subjected to a cooling treatment, unusually low viscosity casein can be produced. Conversely, by using auxiliary air to heat treat the casein after drying higher viscosity casein can be produced.

The flow of the air and the particles of material through the drier may be induced by suction as well as by propulsion. In Figure 4, for example, an embodiment of the invention is shown wherein the exhaust duct 40 of the chamber 42 is provided with a fan 44 driven by a motor 45. In this embodiment streams of air are drawn into the chamber through conduits 46 and 47 by the suction created by the fan 44. Suitably located dampers 48 and 49 control the flow of air through the conduits 46 and 47, the substance to be dried being fed into the conduit 46 at 50. The exhaust separator 52 which is of the centrifugal type and similar in arrangement to the separator 30 shown in Figs. 1 and 2 separates the particles from the air for deposit in the bin 54.

As shown in Fig. 4, it is sometimes helpful to place a cone-shaped member 60 at the bottom of the drying chamber with the apex thereof extending upwardly toward the exhaust duct. The cone may be spaced from the walls by suitable spacing rods 62. The cone is preferably located so that the conical surfaces thereof are disposed where the main air stream reverses itself in passing from the outer to the inner vortices. Thus, should little or no additional air be introduced at the bottom of the chamber, the conical

surfaces will intercept and direct the gravitating particles upwardly into the inner vortex.

It is to be understood that the cone 60 may be used, not only in the form shown in Fig. 4, but also in the forms shown in Figs. 1, 3 and 5.

Referring to Figure 5 of the drawings, a further embodiment of the invention is illustrated by which my method of drying may be practiced. This form of apparatus comprises a pair of substantially concentrically arranged drying chambers 10 and 12. The wet substance is initially treated to a highly heated stream of air in the outer chamber 10 which surrounds the chamber 12, the chamber 10 being of a size to maintain sufficient velocity to convey the material being dried. A fan 74 propels heated air from a heater 76 through a conduit 78 to which the wet material in a divided form is fed at 80. The propelled air entrains the particles of substance and passes into the chamber 10 through a tangential inlet 82.

The initial stream of heated air and entrained particles are caused to whirl upwardly through the annular chamber 10 which is so proportioned as to maintain a steady upward movement of air to an opening 84 which permits passage of the air and entrained particles tangentially into the upper portion of the inner chamber 12. While the finer particles are quickly conveyed through the opening 84 to the chamber 12, the coarser moisture retaining particles tend to resist the upward movement of the air through the chamber 10. These coarser particles tend to gravitate backward against the incoming air, whereby they are further treated before they pass through the opening 84.

While the drying operation conducted in the chamber 10 may be sufficient to adequately dry part of the solids, further drying and/or heating or cooling treatment may be had in the inner chamber 12. The air and entrained particles entering the chamber 12 pass through whirling movements in substantially the same manner as described in connection with chamber 10 of Fig. 1. Any particles which are of sufficient size and weight to separate from the air and gravitate toward the bottom of the chamber 12 are further treated by an upwardly whirling stream of air introduced by a fan 85 through a conduit 86 disposed tangentially to and near the bottom of the chamber 12. The air introduced through the conduit 86 may be tempered by controlling the admixture therewith of cool air at 87.

A withdrawal duct 88 extending down through the chamber 10 is provided at the bottom of the chamber 12 through which foreign and overweight particles capable of gravitating through the whirling streams of air may be collected and withdrawn from the chamber.

A separator 90 is provided similarly as shown in connection with the embodiment illustrated in Figure 1 for receiving the exhausted air and dry particles from the chamber 12.

While many wet substances can be adequately treated in one drying unit, additional drying units or chambers may be provided as hereinbefore stated depending, of course, upon the amount, wetness and other characteristics of the substance and also upon the efficiency and thoroughness of drying and heating desired.

From the foregoing description it will be readily apparent that wet substances, such as casein curd having a high moisture content, can be rapidly dried without any appreciable increase in the acidity already present in the wet curd.

The dried casein particles are small, porous, fluffy and of a light color. The heating period of the drying process being only a matter of seconds, or prolonged and intensified if desired, a finished casein product can be obtained with either low or high viscosity characteristics, whichever is required.

While several embodiments and variations of my method and apparatus have been shown and described, it is recognized that many additional embodiments and variations are possible. It is to be understood, therefore, that the embodiments shown and described are to be regarded as illustrations of the invention only and not in restriction thereof.

I claim:

1. A method of rapidly drying particles of moist solid substances comprising delivering and whirling a stream of heated air to establish a vortex movement, feeding the particles to be dried into the stream of heated air for entrainment into the vortex to dry the particles, separating from the vortex movement by action thereof the slower drying particles, removing with air from the vortex movement the substantially dried particles, and introducing additional air into the vortex to intercept and retrain the separated particles in the vortex movement.

2. A method of rapidly drying particles of moist solid substances comprising delivering and whirling a stream of heated air to establish a vortex movement, feeding the particles to be dried into the stream of heated air for entrainment into the vortex to dry the particles, separating from the vortex movement by action of the vortex the slower drying particles from the air, removing with air from the vortex movement the substantially dried particles, introducing additional drying air to the vortex flow to intercept, further dry and retrain the separated particles in the vortex movement, and recovering the substantially dried particles from the air removed from said vortex.

3. A method of rapidly drying particles of moist solid substances comprising delivering and whirling a stream of heated air into a chamber to whirl the air downwardly therein in the form of a spiral and then upwardly centrally of the spiral to an exhaust outlet, whereby the slower drying particles are separated out by centrifugal force at the periphery of the whirling air and the more easily dried particles are carried by the air through the exhaust outlet, and introducing and whirling additional drying air into the lower portion of the chamber in the form of an upward spiral to intercept, further dry and retrain in the spiraling flow of the said first mentioned air the separated particles.

4. A method of rapidly drying moist solid particles of casein curd and like substances in a confined space comprising feeding the particles for suspension in a stream of heated air, introducing the air and entrained particles downwardly into said space in the form of a spiral and then upwardly centrally of the spiral, and introducing additional heated air at the bottom of the space to intercept particles to facilitate the drying thereof and their entrainment into the spiraling movement.

5. A method of rapidly drying particles of moist solid substances in a pair of confined intercommunicating superposed spaces, comprising feeding the particles for suspension in a stream of heated air, introducing the air and entrained particles downwardly into the upper space in the

form of a spiral and then upwardly centrally of the spiral, and introducing additional air tangentially into the lower space to form an upward flow of air into the upper space to intercept particles gravitating toward the lower space and thereby further dry the particles and re-entrain them into the spiraling movement.

6. A method of rapidly drying particles of moist solid substances in a plurality of concentrically arranged confined spaces, comprising feeding the particles for suspension in a stream of heated air, introducing the air and entrained particles for movement upwardly into the outer space in the form of a spiral to the upper portion of the outer space, passing the air and particles entrained therein from the upper portion of the outer space tangentially into the inner space for movement downwardly in the form of a vortex, removing the air and the particles entrained therein from the axial portion of the inner space, and introducing additional heated air adjacent the bottom of the inner space to intercept particles released from the stream of air to facilitate the drying of the particles and the reentrainment thereof in said stream.

7. Apparatus for quickly drying particles of moist solid substances comprising means providing a chamber conically shaped at least in part, means for feeding the particles for suspension in a stream of hot air, means for introducing the air and the particles entrained therein tangentially and adjacent the upper portion of said chamber to form a vortex movement in the chamber, an exhaust duct located centrally of the upper portion of said chamber for exhausting the air and substantially dried particles from the axial portion of said chamber, and means for introducing additional air adjacent the bottom of said chamber to intercept particles which gravitate toward the bottom of said chamber to reentrain them in the vortex movement.

8. Apparatus for quickly drying particles of moist solid substances comprising means providing a chamber conically shaped at least in part, means for feeding the particles for suspension in streams of hot air, means for introducing the air and the particles entrained therein tangentially and adjacent the upper portion of said chamber to form a vortex movement in the chamber, an exhaust duct centrally of the upper portion of said chamber for exhausting the air and the particles maintained in suspension from the axial portion of said chamber, means for introducing additional air adjacent the bottom of said chamber to intercept moisture retaining particles gravitating toward the bottom of said chamber to reentrain them in the vortex movement, and means for removing the particles from the air exhausted from said chamber.

9. Apparatus for quickly drying particles of moist solid substances comprising means forming a chamber conically shaped at least in part, means for feeding the particles for suspension in a stream of hot air, means for introducing the air and the particles entrained therein tangentially and adjacent the upper portion of said chamber to form a whirling movement therein, means providing an exhaust duct centrally of the upper portion of said chamber for exhausting the air and particles maintained in suspension therein from said chamber, the coarser moisture retaining particles being separated from the air and gravitating toward the bottom of the chamber, and means for introducing additional hot air tangentially and adjacent the bottom of said

chamber to dry and entrain the separated particles for reentrainment in said whirling movement for removal through said exhaust duct.

10. Apparatus for quickly drying particles of moist solid substances comprising means providing a chamber conically shaped at least in part, means for feeding the particles of substance for suspension in a stream of hot air, means for introducing the air and the particles entrained therein tangentially and adjacent the upper portion of said chamber to form a vortex movement in the chamber, the coarser moisture retaining particles of substance and any relatively heavy particles of foreign material present being separated from the air by centrifugal force and gravitating toward the bottom of said chamber, means for introducing adjacent the bottom of said chamber an upward flow of additional air to further dry and entrain the separated particles of substance for reentrainment in the vortex movement, an exhaust duct for the air and entrained particles located substantially coaxially of said chamber, and means at the bottom of said chamber for removing the particles gravitated through said additional flow of air.

11. Apparatus for quickly drying particles of moist solid substances comprising means providing a chamber conically shaped at least in part, means for feeding the particles for suspension in a stream of hot air, means for introducing the air and the particles entrained therein tangentially and adjacent the upper portion of said chamber, an exhaust duct located centrally of the upper portion of said chamber for exhausting the air and substantially dried particles from said chamber, a second chamber communicating with the bottom of the first mentioned chamber, and means for introducing air tangentially into said second chamber for passage upwardly into the first mentioned chamber to intercept and thereby facilitate the drying of particles gravitating to the bottom of said first mentioned chamber.

12. Apparatus for quickly drying particles of moist solid substances comprising means providing a chamber conically shaped at least in part, means for feeding the particles for suspension in a stream of hot air, means for introducing the air and the particles entrained therein tangentially and adjacent the upper portion of said chamber to form a vortex movement in the chamber, an exhaust duct located centrally of the upper portion of said chamber so that the vortex movement is reversed and the air and entrained particles move in the form of a smaller vortex centrally of the first mentioned vortex movement, means to establish a suction through said exhaust duct, and means to permit the entrance of additional air adjacent the bottom of said chamber to intercept particles gravitating towards the bottom of the chamber and to retrain them into the aforementioned vortex movements.

13. Apparatus for quickly drying particles of moist solid substances comprising means providing a pair of similarly shaped chambers at least in part of coaxial form, one of the chambers being disposed in spaced relation to and within the upper portion of the other, means providing an opening arranged tangentially to said inner chamber and adjacent the upper portion thereof for communication with the outer chamber, means for feeding particles of the substance to be dried for suspension in a stream of hot air, means for introducing the air and the particles

of substance entrained therein tangentially adjacent the bottom portion of the outer chamber for upward whirling movement to and through the tangential opening into the inner chamber, means providing an exhaust duct centrally of the upper portion of said inner chamber, and means communicating adjacent the bottom of the inner chamber for introducing additional air into said inner chamber to facilitate the drying operation.

14. Apparatus for quickly drying particles of moist solid substances comprising means providing a chamber conically shaped at least in part, means for feeding the particles for suspension in a stream of hot air, means for introducing the air and the particles entrained therein tangentially and adjacent the upper portion of said chamber to form a vortex movement in the chamber, an exhaust duct located centrally of the upper portion of said chamber so that the vortex flow is reversed to exhaust the air and substantially dried particles from said chamber, a cone disposed in said chamber with the apex extending upwardly therein, means to support said cone in spaced relation to the sides of said chamber, and means for introducing additional air into said chamber for flow upwardly between said

cone and the sides of said chamber to intercept particles released from the vortex movement to further dry and retrain them in the vortex.

15. Apparatus for quickly drying particles of moist solid substances comprising means providing a chamber conically shaped at least in part, means for feeding the particles for suspension in a stream of hot air, means for introducing the air and the particles entrained therein tangentially and adjacent the upper portion of said chamber, an exhaust duct located centrally of the upper portion of said chamber for exhausting the air and substantially dried particles from said chamber, a second chamber having a port communicating upwardly into the bottom of the first mentioned chamber, means for introducing an additional stream of air tangentially into said second chamber for passage through said port into said first mentioned chamber to facilitate the drying of particles gravitating to the bottom of said first mentioned chamber, and means associated with said port to direct the additional air upwardly axially of said first mentioned chamber.

WILLIAM B. WINTER.
